UNITED STATES PATENT OFFICE.

HOMER N. MOTSINGER, OF PENDLETON, INDIANA, ASSIGNOR TO MOTSINGER DEVICE MANUFACTURING COMPANY, OF PENDLETON, INDIANA, A CORPORATION OF INDIANA.

SPEED-CONTROLLING GOVERNOR.

SPECIFICATION forming part of Letters Patent No. 710,597, dated October 7, 1902.

Application filed February 15, 1902. Serial No. 94,228. (No model.)

To all whom it may concern:

Be it known that I, HOMER N. MOTSINGER, a citizen of the United States, residing at Pendleton, in the county of Madison and State of Indiana, have invented certain new and useful Improvements in Speed-Controlling Governors, of which the following is a specification.

My invention relates to an improvement in means for controlling the speed for a rotary shaft, being especially designed for use in connection with a sparking dynamo for gas-engines, as shown in my Patent No. 642,869.

In the use of dynamos of the class described the pulley of the dynamo is held in automatic intermittent contact with the periphery of a driving-pulley, such as the fly-wheel of the engine, and the point of application to the driving-pulley, either above or below its axis, depends upon circumstances.

The object of my invention is therefore to produce mechanism which shall be efficient and sensitive for causing intermittent contact, preferably intermittent peripheral contact, between the driving and driven pulleys and of such character that by a slight shifting of parts the machine may be applied either above or below the axis of the driving-pulley.

The accompanying drawing, which is a perspective view, illustrates my invention as applied to my present form of sparking dynamo.

In the drawing, 1 indicates a dynamo provided with an armature-shaft 2 and driven pulley 3. The dynamo is pivotally supported in a base 4 on an axis 5, which axis is external to the axis of the shaft 2, being in the present case at right angles thereto.

Secured to shaft 2 is a pair of arms 6, to each of which is pivoted a ball-lever 7, the inner end 8 of which engages a flange 9 of a head 10, sleeved upon shaft 2 and longitudinally movable thereon. Head 10 is provided with a small axial pin 11, which engages a hardened plate 12, carried by the upper end 13 of a lever pivoted at 14 to the base and provided with an arm 13' opposite arm 13, and at equal distances from the pivot 1 I provide points 15 and 16, to either of which 50 may be pivoted one end of a link 17, the op-

posite end of which is pivoted at 18 to the body of the dynamo 1. Link 17 is preferably provided with a central opening 19, through which extends a spring 20, one end of which is attached to a standard 21, carried by the base, and the other end of which is attached to an adjusting-rod 22. Rod 22 passes through one arm 13 of the lever and carries at its outer end an adjusting-nut 23, longitudinally adjustable on the rod and adapted to engage the arm 13, so as to cause spring 20 to draw plate 12 against pin 11 of head 10, at the same time acting upon the body of the dynamo through link 17.

In operation when link 17 is attached as shown in full lines in the drawing the tendency of spring 20 is to throw pulley 3 up about the axis 5, and when the shaft 2 is rotated the governor-balls 7 will fly out, so as to shift head 10 on the shaft, and by pressing it against plate 12 arm 13 swings the lever to the right and causes link 17 to swing the dynamo about the axis 5 in the opposite direction. By connecting link 17 to arm 13 of the lever, as shown in dotted lines in the drawing, the action of spring 20 upon the parts is reversed.

I claim as my invention—

1. In a speed-controlling governor, the combination with a shaft-bearing, of a shaft mounted therein, a pivotal support for the shaft-bearing outside the shaft-axis, a lever pivoted upon the support, a speed-controlled governor carried by the shaft and engaging the lever, and a connection between the lever and the shaft-bearing, substantially for the purpose set forth.

2. In a speed-controlling governor, the combination with a shaft-bearing, of a shaft mounted therein, a pivotal support for the shaft-bearing outside the shaft-axis, a lever pivoted upon the support, a speed-controlled governor carried by the shaft-bearing, and means for connecting either arm of the lever to the shaft-bearing, for the purpose set forth.

3. In a speed-controlling governor, the combination with a shaft-bearing, of a shaft mounted therein, a pivotal support for the shaft-bearing outside the shaft-axis, a lever pivoted upon the support, a head axially mov-

able upon the shaft and adapted to engage one arm of the lever, speed-controlled means carried by the shaft and adapted to shift the head upon the shaft, a link connecting said lever with the shaft-bearing, and a spring urging said lever into engagement with the sliding head.

4. In a speed-controlling governor, the combination with a shaft-bearing, of a shaft 10 mounted therein, a pivotal support for the shaft-bearing outside the shaft-axis, a lever pivoted upon the support, a head axially movable upon the shaft and adapted to engage one arm of the lever, speed-controlled means 15 carried by the shaft and adapted to shift the head upon the shaft, a link connected to the shaft-bearing, and means for attaching said link to either arm of the lever.

5. In a speed-controlling governor, the combination with a suitable support, of a shaft 20 and pulley carried thereby, a speed-controlled

governor carried by said shaft, a lever engaged by said speed-controlled governor, and intermediate connections for connecting either arm of the lever to the pulley whereby 25 the speed-controlled governor will automatically shift the pulley.

6. In a speed-controlling governor, the combination with a suitable support, of a shaft and pulley carried thereby, a speed-controlled 30 governor, a lever engaged by said speed-controlled governor, and intermediate connections for connecting either arm of the lever to the pulley whereby the speed-controlled governor will automatically shift the pulley. 35

In witness whereof I have hereunto set my hand and seal at Indianapolis, Indiana, this 8th day of February, A. D. 1902.

HOMER N. MOTSINGER. [L. S.]
